(57) **CLAIM**

The ornamental design for a fan assembly, as shown and described.

DESCRIPTION

FIG. 1 is a front, bottom perspective view of a fan assembly showing our new design;

FIG. 2 is a rear elevational view showing the design for the fan assembly of FIG. 1;

FIG. 3 is a right side elevational view showing the design for the fan assembly of FIG. 1;

FIG. 4 is a top plan view showing the design for the fan assembly of FIG. 1; and,

FIG. 5 is a bottom plan view showing the design for the fan assembly of FIG. 1.

In FIGS. 1–5, the broken line showing of various items including (i) the central vertical support member (FIGS. 1–4), (ii) a portion of the ceiling to which the central vertical support member is attached (FIG. 1), (iii) an upper portion of the motor housing portion (FIG. 4), (iv) the fan blades and associated mounting apparatus (FIGS. 1–5), and (v) the fastener member located at the lower apex of the fan assembly (FIGS. 1–3 and 5) is for illustrative purposes only and forms no part of the claimed design.
